SPECTACLE FRONT

Austin B. Belgard, Evanston, Ill.

Application April 10, 1956, Serial No. 40,990

Term of patent 14 years

(Cl. D57—1)

Fig. 1 is a front view in elevation of a spectacle front showing my new design;

Fig. 2 is a rear view in elevation; and

Fig. 3 is an enlarged sectional detail view, the section being taken as indicated at line 3—3 of Fig. 1.

The characteristic features of my design for the spectacle front disclosed reside in the notched link portions having the configurations shown.

I claim:

The ornamental design for a spectacle front, as shown and described.
